[57] ABSTRACT

A collapsible chair having interconnected forward and rearward legs with a chair back element mounted on the rearward legs and a chair seat element mounted solely on the forward legs, the legs being so interconnected as to permit the forward legs to be shifted upwardly along the rearward legs during collapse of the chair so that the seat element is shifted completely upwardly during chair collapse.

SHEET 2 OF 2

FIG. 2

FIG. 4

FIG. 5

COLLAPSIBLE CHAIR

This invention relates generally to a collapsible chair wherein the seat portion is shifted upwardly during the chair collapse. More particularly, the invention relates to a collapsible chair, or a foldable grandstand chair, wherein the chair is fully collapsed during folding movement of a grandstand.

Heretofore, chairs mounted on foldable grandstands used in auditoriums and elsewhere are normally of such a bulky construction that it becomes difficult to collapse the chairs during grandstand folding without occupying an undue amount of floor space. On the other hand, should the chairs be designed specifically for complete collapse within a small space, they are many times rendered not only unsightly, but quite uncomfortable. The present invention avoids these difficulties by providing a collapsible chair especially for use with a foldable grandstand wherein the chair not only does not interfere with the folded decks of the grandstand, but it moreover presents an exceptionally good appearance since it does not resemble the standard type folding chair.

It is therefore a principal object of the present invention to devise a chair which may be neatly and compactly collapsed as its forward legs are shifted upwardly with respect to its rearward legs, the seat element being so attached to the rearward legs that it too moves upwardly during chair collapse out of interference with the folded grandstand deck.

Another object of this invention is to provide such a collapsible chair wherein the front and rear chair legs are interconnected by means of link members which permit such a shifting movement.

A further object of the present invention is to provide such a chair wherein the chair back element is pivotally mounted to the rear legs so as to be movable between a vertical position and a rearwardly tilted position.

A still further object of this invention is to provide such a chair wherein said bracket plates having elongated openings therein are mounted on the chair back to facilitate its pivotal movement.

A still further object of this invention is to provide such a chair wherein arm rest elements are fixedly secured to the front legs so as to be also shifted therewith during chair collapse.

A still further object of the present invention is to provide such a chair wherein the front legs are pivotally secured to the grandstand deck which, when folded, serves to shift the front legs upwardly along the rear legs into the collapsed position.

A still further object of the invention is to provide such a collapsible chair wherein the chair back is pivotally secured at the level of the next highest grandstand deck so that, when such deck is folded, it serves to move the chair back into a vertical position of complete chair collapse.

Other objects, advantages and novel features of the invention will become apparent from the following description of the invention when considered in conjunction with the accompanying drawings, wherein:

FIG. 1 is a side elevational view of a collapsible chair in accordance with the present invention in its uncollapsed condition mounted in place on a grandstand shown only in part;

FIG. 2 is similar to FIG. 1 except that the chair is shown in its fully collapsed condition;

FIG. 3 is a sectional view of the arrangement taken along the line 3-3 of FIG. 1 showing the details of adjacent chairs as they are related to one another;

FIG. 4 is a sectional view taken along the line 4-4 of FIG. 1; and

FIG. 5 is a sectional view taken along the line 5-5 of FIG. 1.

Turning now to the drawings wherein like reference characters refer to like and corresponding parts throughout the several views, a collapsible chair 10 constructed in accordance with the present invention is shown mounted on a grandstand 11, a full deck level of which is shown in FIGS. 1 and 2 along with a portion of a higher deck level. Vertical uprights 12 and 120 of the grandstand comprise the rear legs for the respective chairs along each grandstand tier. Adjacent uprights in each row (only one of which is shown in FIG. 3) are designated *a*, etc. A foldable deck extends between uprights 12 and 120 as shown in FIG. 1, the deck comprising sections 13a and 13b hinged together by means of hinges 14a and 14b such that the hinge plates of each are secured respectively to the under sides of sections 13a and 13b and to the side walls of a tubular transverse support structure 15. The opposite ends of each deck section are hingedly secured by means of hinges 16a, 16b to their respective uprights 120 and 12. The next higher deck section 113a is hingedly secured by means of hinge 116a to the uprights 12, 12a, etc. Of course, the grandstand platform at each level is repeated for levels higher and lower than that shown in FIG. 1, it being understood that FIG. 1 is exemplary only of a typical grandstand tier at a single level.

Front legs 19 and 19a for each chair are channel-shaped in cross section, as shown in FIG. 3, and the lower ends of each are pivotally secured as at 21 to the deck section 13b between the section ends. A front leg 19 is associated with its rear leg or upright 12 and is connected therewith by means of link members 22, 122 extending between a bolt 23 located near the top of uprights 12 and bolt 24 located on leg 19 as shown in FIG. 5. Each link member 22, 122 is disposed along the inner sides of the channel legs of member 19.

Link members 22a, 222 serve to interconnect forward leg 19a with upright 12a in the same manner as described with reference to legs 12 and 19. These two pair of interconnected leg members therefore define chair 10 which is typical for an adjacent chair 100 sharing legs 12 and 19, and which is also typical for an adjacent chair 200 sharing legs 12a, 19a. Obviously, other adjacent chairs are provided for each row of the grandstand and are each typically constructed in accordance with the FIG. 3 showing.

A chair back element 25, which may be cushioned or upholstered or finished in some other manner, spans an adjacent pair of rear legs 12, 12a for each chair and is secured to each rear leg by means of bolts 23, 23a and bolts 26, 26a. A side bracket plate 27, 27a is secured in any conventional manner to the rear surface of back element 25 along opposite sides thereof as shown in FIG. 3. An elongated slightly arcuate opening 128, 28, 28a, 228 (only one of which is conveniently shown in FIG. 1) is respectively provided in bracket plates 127, 27, 27a, 227. The bracket plates 127, 27, 127a, 227 are secured to their respective front legs 19, 19a along opposite sides of each thereof. FIG. 4 illustrates the manner of pivotally securing bracket plates 127, 27 to forward leg 12 by means of bolt 26. With such a construc-

tion, the seat back element 25 may be moved between its rearwardly tilted position shown in FIG. 1 and forwardly toward a vertically upright position as shown in FIG. 2. Obviously, the elongated openings provided in each of the bracket plates facilitate movement of the chair back elements between these two positions as the side bracket plates slide along bolts 23.

A chair seat element 29 spans an adjacent pair of forward legs 19, 19a and is secured thereto by means of bracket plates 31. Such plates, (only one of which is shown) may be each provided with protuberances 32 fixed along the inner surfaces thereof for cooperation with protuberances 30,30 fixed on the opposite sides of the seat to thereby maintain the seat in its unfolded position as shown in FIG. 1. Of course, the chair seat element 29 is movable to a position lying parallel to the front legs 19 in a collapsed condition of the chair, as shown in FIG. 2.

An upholstered or otherwise covered arm rest element 33 (only one of which is shown) is fixedly secured as by welding to the upper end of each forward leg so as to be fully movable therewith during chair collapse.

Operation of the collapsible chair is as follows with reference to FIGS. 1 and 2: A folding of the grandstand at each deck level causes the uprights or rear legs 120 to be moved toward the rear legs 12 as the deck sections 13b and 13a of a typical grandstand deck 11 are folded along transverse support strut 15. As deck section 13b pivotally moves upwardly about its hinge 16b, it carries with it the forward legs 19, 19a for a typical chair 100 (and for the remaining chairs in the row) and causes these legs to shift upwardly along their respective rearward legs 12, 12a. During such upwardly shifting movement, the forward legs pivot about bolts 23 and 24 and about hinge 21 so as to be moved from a position as shown in FIG. 1 to the position of full chair collapse as shown in FIG. 2. Since both the seat element 29 and the arm rests 33 are mounted solely on the forward legs 19, 19a, they too are shifted upwardly and, in the process the chair seat element 29 is caused to be pivoted into a substantially vertical position as shown in FIG. 2. When the chair is fully collapsed, it can be seen from FIG. 2 that the bottom of the chair seat element 29 has cleared the folded deck sections 13a, 13b so as to completely avoid any interference therewith. Consequently, the chair seat element and the fixed arm rests are shifted upwardly completely out of interference with the folded deck sections of the grandstand tier 11. This is a typical collapsing arrangement for the remaining chairs at the grandstand level 11 as well as for all the remaining levels of a multi-tiered grandstand.

As the folding of the grandstand continues after the chairs at level 11 have been collapsed as above-described, the next highest tier behind the chair shown in FIG. 1 is of course collapsed in a similar manner. For example, deck section 113a pivots upwardly about its hinge 116a and, in the process of so doing, moves from a position shown in phantom to that shown in full lines in FIG. 2 to thereby cause the chair back elements 25 to be pivotally moved about bolts 26 toward uprights 12 and into a substantially vertical position as shown in FIG. 2. The chair is therefore fully collapsed and by reason of its unique construction occupies a minimum amount of space on the folded grandstand.

From the foregoing, it can be seen that a collapsible chair for a grandstand has been devised which uses a minimum number of connection points for assembling

the chair and, when collapsed, occupies a minimum amount of space thereby enhancing both the practicality and the economy of both the construction and the operation of the arrangement. The chair seat is folded to a position as near as possible to the back seat element of each chair which is of a simple yet durable and safe design for auditorium and other uses. The arm rests for each chair are welded or otherwise fixedly secured directly to the front chair legs themselves thereby further enhancing the rigidity of the arrangement. To avoid the appearance of a folding arrangement, the link members 22 are each disposed between the rear legs and the forward legs of each chair so as to be completely hidden from the viewer. Also, the forward legs completely cover the upper portions of their respective rearward legs when lowered into the position as shown in FIG. 1. Additional lateral support and rigidity is therefore conveniently achieved. The hinge plate 21 for the lower portion of the vertical chair legs which is attached to each deck level of the arrangement is continuous and extends between adjacent forward legs of the chair in order to provide greater strength, permanency and rigidity for the hinge.

Obviously, many modifications and variations of the present invention are possible in the light of the above teachings. It is therefore to be understood that within the scope of the appended claims the invention may be practiced otherwise than as specifically described.

What is claimed is:

1. A collapsible chair comprising, interconnected forward and rear legs, said forward legs being channel-shaped in cross-section and opening toward said rear legs, link members interconnecting said legs together, each said respective link members being pivotally secured at one end to each said rear leg near one end thereof, the other end of each said respective link members being pivotally secured to each said forward leg at the inner sidewalls thereof and between the ends thereof, a chair back mounted on said rear legs, brackets on said forward legs, a chair seat located between said brackets and being pivotally connected thereto, stop elements lying in a horizontal plane on opposite sides of said chair seat and extending toward said respective brackets and being disposed on opposite sides of the pivotal connection of said chair seat, other stop elements on said respective brackets extending toward said respective sides of said chair seat, the forward and rear ones of said other stop elements being in contacting engagement with and lying respectively below and above said stop elements on said opposite sides of said pivotal connection when said chair seat is in a substantially horizontal position, said contacting stop elements serving to solely support said chair seat in its horizontal position, and said link members permitting said forward legs to be pivoted upwardly with respect to said rear legs until said link members and a portion of said rear legs are received within the open channels of said forward legs.

2. The collapsible chair according to claim 1 wherein said chair back is pivotally connected at the lower end thereof to said rear legs, bracket plates on opposite sides of said chair back and having arcuate openings therein, said bracket plates extending forwardly of said chair back, bolt means securing said chair back to said rear legs through said arcuate openings, whereby said chair back is movable about its pivotal connection be-

tween a rearwardly inclined position and a position lying coaxial with said rear legs.

3. A collapsible chair according to claim 2 wherein a chair arm member extending forwardly of said forward legs is fixedly secured to each of said forward legs at the top ends thereof.

4. A collapsible chair for a foldable grandstand comprising, interconnected forward and rear legs, said forward legs being channel-shaped in cross-section and opening toward said rear legs, link members interconnecting said legs together, each said respective link members being pivotally secured at one end to each said rear leg near one end thereof, the other end of each said respective link members being pivotally secured to each said forward leg at the inner sidewalls thereof and between the ends thereof, a chair back mounted on said rear legs, brackets on said forward legs, a chair seat located between said brackets and being pivotally connected thereto, stop elements lying in a horizontal plane on opposite sides of said chair seat and extending toward said respective brackets and being disposed on opposite sides of the pivotal connection said chair seat, other stop elements on said respective brackets extending toward said respective sides of said chair seat, the forward and rear ones of said other stop elements being in contacting engagement with and lying respectively below and above said stop elements on said opposite sides of said pivotal connection when said chair seat is in a substantially horizontal position, said contacting stop elements serving to solely support said chair seat in its horizontal position, a stepped fold-

able grandstand constituted by a series of multi-level decks, one of said decks being hingedly secured to said rear legs, said forward legs being hingedly secured to said one deck, each said deck being upwardly foldable between its ends so that when said one deck is folded upwardly between its ends, said forward legs are shifted upwardly with respect to said rear legs until said link members and a portion of said rear legs are received within the open channels of said forward legs.

10 5. The collapsible chair according to claim 4 wherein said chair back is pivotally connected at the lower end thereof to said rear legs, bracket plates on opposite sides of said chair back and having arcuate openings therein, said bracket plates extending forwardly of said chair back, bolt means securing said chair back to said rear legs through said arcuate openings, whereby said chair back is movable about its pivotal connection between a rearwardly inclined position and a position lying coaxial with said rear legs.

15 20 6. The collapsible chair according to claim 5 wherein said back element is pivotally secured at one end to said rear legs at a level of the adjacent next higher grandstand deck, whereby said back element is movable to said coaxial position by said adjacent deck during the folding thereof.

25 20 7. The collapsible chair according to claim 4 wherein a chair arm member extending forwardly of said forward legs is fixedly secured to each of said forward legs at the top ends thereof.
